UNITED STATES PATENT OFFICE.

WILLIAM H. HOOPER, OF SWAMPSCOTT, MASSACHUSETTS, ASSIGNOR, BY MESNE ASSIGNMENTS, TO THOMAS G. PLANT, OF BOSTON, MASSACHUSETTS.

CHANNEL-MOISTENING DEVICE FOR SOLE SEWING OR FASTENING MACHINES.

No. 889,375.

Specification of Letters Patent.

Patented June 2, 1908.

Application filed June 5, 1906. Serial No. 320,280.

To all whom it may concern:

Be it known that I, WILLIAM H. HOOPER, a citizen of the United States, residing at Swampscott, in the county of Essex, State 5 of Massachusetts, have invented an Improvement in Channel-Moistening Devices for Sole Sewing or Fastening Machines, of which the following description, in connection with the accompanying drawings, is a 10 specification, like letters on the drawings representing like parts.

This invention relates to channel wetting or moistening devices employed in connection with sole sewing or fastening machines 15 in the manufacture of boots and shoes.

My invention is applicable to all types of sole stitching or fastening machines, it being 20 equally immaterial whether said machines are of the McKay or horn type, or of that employed in welt sewing, fair stitching or for applying metallic fastenings.

In the types of machines to which reference has been made, the fastenings employed are usually laid in a channel formed in the 25 sole, and to cause the stock of which the sole is composed more readily to be penetrated by the fastenings or the fastening inserting devices, it should be suitably treated with a moistening liquid such, for example, as 30 water.

As heretofore constructed some of the machines of the type referred to, are provided with automatic devices for supplying water to the sole channel during operation 35 of the stitching mechanisms, the same acting either periodically or continuously. The periodic moistening devices are operated by being connected with a moving part of the machine and the continuous moistening devices 40 supply water uninterruptedly during the operation of the machine by connection with the starting and stopping treadle, the movements of the latter opening and closing a controlling valve in the supply pipe of the 45 moistener. The former type is objectionable owing to the constant wear of moving parts with consequent leakage and the latter type is objectionable owing to the fact that its operation is restricted solely to the times 50 of starting and stopping the machine.

My invention aims to provide an efficient moistening device that is not connected with the starting and stopping mechanism or the clutch treadle, but which may be operated 55 upon starting the machine so as to insure

supplying the tempering liquid to and in advance of the stitching or fastening mechanism and permit it to remain continuously in operation until the release of the clutch or the actuation of the stopping mechanism 60 when it may be cut out of operation either with or independently of the stopping of the machine.

The above, however, with other objects and features of my invention will be best 65 understood and appreciated from the following description, when taken in connection with the accompanying drawings of a machine embodying one form of my invention and selected for purposes of illustration, its 70 scope being particularly pointed out in the appended claims.

In the drawings:—Figure 1, in front elevation, partially broken away, illustrates an embodiment of my invention, selected for 75 purposes of illustration, in which the moistening device is used in connection with a waxed-thread chain stitch shoe sewing machine of the type used in the manufacture of welt and turned shoes; Fig. 2 is an enlarged 80 vertical section taken on the line 2—2, Fig. 1, to show the mechanism for closing the valve of the moistening device and its connections in normally closed or inoperative position; Fig. 3, a similar view showing the 85 valve closing mechanism elevated in position to open said valve; Fig. 4, a detail on the line 4—4, Fig. 1, showing the actuating lever for operating the valve mechanism; and Fig. 5, an enlarged detail representing a bottom view of a channel guide constituting the 90 nozzle of the moistening device.

In the particular embodiment of my invention selected for illustration herein and shown in the drawings, referring first to Fig. 95 1, the machine column A, its head B and the various working parts supported thereon may be of any desired type of construction, as for example, a common and well known type of commercial machine of the waxed-thread chain stitch welt type employed upon 100 welt and turned shoes.

The machine shown is operated (see Fig. 1) from a friction driving disk, 1, fast on a power shaft, 2, which is suitably journaled 105 in or at the base of the column, and is provided with a co-operating loosely mounted pulley, 3, connected by a belt, 4, with an overhead pulley or drive wheel, 5, on the main or operating shaft, 16, of the machine. 110

The disk, 1, and loose pulley constitute one form of a friction clutch the members of which, in accordance with the usual practice, are adapted to be moved into engagement with or separated from one another by means of a suitable treadle, in the present instance, shown as a horizontal treadle, 6. This treadle is suitably mounted at the side of the machine upon a rock shaft, 7, and has an upright arm, 8, forked at its upper end to engage the grooved periphery of the hub of said loose pulley, 3, to cause the latter to be moved toward and from the fixed disk, 1, at will.

15 It will be unnecessary to give a detailed description of the construction and operation of the stitch forming mechanism of this machine, as such is well known and understood. It will be sufficient here to refer to the usual channel guide *a*, adapted to run in the channel of the sole and guide it into operative position, the awl, 50, the needle directly behind it (but not shown), the looper, 70, and a work support, 18, all of which may be of usual and well known construction and operation. While any suitable moistening liquid may be supplied, in the present instance, water is employed, the same being stored within a reservoir or tank, 9, suitably mounted above and adjacent the stitch forming mechanism and having an outlet, 10 controlled by a valve, 13, from which leads an outlet pipe, 11, communicating, in the present instance of my invention, with a longitudinal opening or passage, 12, (see Fig. 5), in said channel guide *a*. The outlet end of said passage is adjacent the lower end of said guide end, so that water flowing through said passage will be directed into the channel 40 of the sole in advance of said awl and needle.

By this construction the moistening of the sole is restricted to the channel and the subjacent parts of the sole, thereby preventing staining, spotting and buckling of the sole surface produced by the manual application of water, or where water is permitted to flow freely from a can or funnel and supply pipe. My invention, however, is not limited to such construction and contemplates the employment of any suitable part of the machine as a nozzle to direct the moistening liquid to and upon the work.

The amount or supply of water may be regulated by the valve, 13 (Figs. 2 and 3), which is provided at the connection of the supply pipe, 11, with said tank, 9. This valve is provided with a lever arm, 14, connected by a link or rod, 15, to a bell crank, 19, pivoted at 20 intermediate the ends of its long arm, to a bracket, 21, secured to a fixed part of the machine, the vertical oscillations of this long arm, opening and closing said valve. For oscillating this bell crank, its short arm is provided with a slot, 22, to receive a slide block, 23, arranged to slide

freely therein, (shown in dotted lines in Figs. 2 and 3). This block carries a roller, 24, loosely pivoted thereon by a stud bolt or pin, 25, which also forms the pivotal connection for a rod or link, 26, which is operated by means of a suitable actuating lever, 27 (Fig. 4), here shown as a treadle lever. This lever is not the starting and stopping lever of the machine but is pivoted as at 28 upon the foot of the column A having its outer or free end curved forwardly to a position, it may be, close beside the said starting and stopping treadle, 6 (Figs. 1 and 4), so that when desired the two may be depressed or released simultaneously or either may be operated independently of the other.

By reference to Figs. 2 and 3, it will be apparent that as the link or rod, 26, is elevated, the slide block, 23, will first rise to the top of said slot, 22, before movement of said bell crank results, and that continued upward motion of said block will swing said bell crank to depress the link, 15, and said valve lever, 14, to open said valve, 13, and permit water to flow to the channel guide. When however, the rod or link, 26, is permitted to drop the block, 23, will slide down the bell crank slot, 22, carrying the roller, 24, with it towards the lower end of said slot, but without moving the bell crank, 19, and the connections intermediate it and said valve, 13.

While my invention contemplates several methods or arrangements of suitable mechanism for operating and controlling the movements of this rod, 26, I have, in the present instance shown but one, now to be described, though I wish it to be understood that the invention is for any means for securing the results set forth and is not limited to the specific mechanism shown and described.

The lower end of said rod, 26 (Fig. 4), has a roller 30, which rests upon an edge cam, 31, pivotally mounted upon a bracket, 32, at the foot of the column, a guide, 33, being formed upon or connected with this bracket to direct the vertical movements of said rod, 26. This cam has a portion of less diameter against which said roller, 30, normally rests and a high part, 34, or portion of greater diameter, to which said roller is moved by the rotation of said cam, so that the rod, 26, is elevated thereby. To rotate or oscillate this cam about its axis, it is provided with a pinion, 35, which is in mesh with a vertical segmental gear or rack, 36, formed in a head, 37, at the inner end of said actuating treadle 27 and which is suitably slotted to receive said pinion, 35, the teeth of said rack, 36, being formed at a side of said slot and causing rotation or oscillation of the pinion and said cam upon elevation or depression of the tread end, 38, of said actuating treadle. The outer arm of this treadle (see Figs. 1 and 4) is curved forwardly and its tread end, 38, extends forwardly beside and slightly above

the tread end, 39, of the starting and stopping or clutch operating treadle, 6. Upon depressing the former the pinion and cam will be rotated sufficiently to cause the rod 5 roller, 30, to ride up and rest upon the high part, 24, of the cam, thus to elevate the rod and open the valve of the moistening device as already described.

By referring to Figs. 1 and 4, it will be apparent that the actuating lever or treadle, 27, may be depressed sufficiently to open the said valve simultaneously or immediately preceding the starting of the machine by the operative causing his foot to actuate both 15 treadles. In stopping the machine, the tread end, 38, of the actuating lever, 27, must be elevated above the elevated or normal position of the starting and stopping treadle (see Fig. 1) before the cam will be 20 turned sufficiently to permit the roller to drop into the depressed or low part of its cam, but which does not, however, move the bell crank to close the valve. By this arrangement such partial release of the friction 25 clutch may be made as is desired to cause the stitching or fastening mechanism to operate slowly upon difficult portions of the work or whenever desired, and such release may be made without permitting the tread 30 end, 38, of the actuating lever to rise sufficiently to permit the drop of said roller, 30, and its rod, 26, to render effective the machine or power operated mechanism for closing the valve of the moistening device now 35 to be described. Since the drop of the rod, 26, does not move the bell crank, 19, it is necessary to provide other means than said treadle, 27, and its connections to close the valve of the moistening device, and this 40 means should not be a spring or its equivalent because of the unreliability of springs and the fact that they impose additional labor in moving the parts against the operation of the spring. I have therefore provided 45 the main shaft with a cam, 29 (see Figs. 2 and 3), the outer or active end of which normally clears said roller, 24, in either the highest or lowest position of the latter, but as the slotted arm of the bell crank 50 is elevated in opening the valve, 13, it is swung into such a position that the roller will move into the path of said cam, as its carrying block, 23, slides down in the bell crank slot, 22. During this movement the 55 adjacent or active end of the rotating cam, 29, strikes said roller as the latter reaches the position indicated by dotted lines in Fig. 3 and knocks it down to the bottom of the bell crank slot, 22, simultaneously rocking or 60 swinging the bell crank, 8, on its pivot positively or toward the right (Figs. 2 and 3), causing the elevation of the link, 15, and the valve lever, 14, thus shutting off the water. By this construction the means for shutting 65 off the water supply is entirely independent

both in construction and operation of the starting and stopping treadle, though said means may be operated simultaneously with the latter if desired or at any other time.

My machine operates as follows:—The 70 starting treadle, 6, is depressed to cause the movable clutch member or said pulley, 3, to frictionally engage said rotating friction disk, 1, thereby rotating said pulley, 3, the drive wheel, 5, connected therewith, and operating the stitching mechanism in the usual manner. The operative may if he so desire cause his foot to rest upon both treadles, so that the valve actuating treadle is operated simultaneously upon starting the machine 80 to swing said bell crank to open the valve of the moistening device in the manner described. As long as both treadles are held depressed the stitching mechanism will continue to operate and the moistening device 85 will supply water uninterruptedly in advance of said stitching mechanism to temper the stock operated upon by the latter. If desirable, however, the operative may, by the depression of the actuating lever, 27, 90 open the valve of the moistening device prior to or subsequently to the starting of the machine and he may cause it to be closed through the release of the actuating treadle, 27, either before or after the release of the 95 starting and stopping treadle, 6. Thus the water may be caused to flow continuously, intermittently or it may be supplied periodically during the operation of the machine at such times as may be desired. The valve of 100 the moistening device, however, can only be closed through the operation of the machine itself, the release of the actuating lever, 27, only permitting the roller carrying block to slide down the bell crank slot which by the 105 position it assumes upon release of said lever, causes the roller to move into the path of the rotating cam, 29, which by its rotation will strike said roller and close the valve of the moistening device in the manner described.

By my invention suitable moistening liquid may be supplied continuously to the fastening mechanism to flow uninterruptedly while the machine is in operation or the supply may be turned on or off at will, the valve actuating mechanism being under the control of the operative. By using power operated means, such as the cam, to close the valve or render the moistening device ineffective, the use of springs for the same purpose is avoided thereby producing a more reliable device and resulting in a saving of labor on the part of the operative as already pointed out. Furthermore, the water tank or receptacle being mounted directly over the stitching mechanism, a comparatively short length of pipe is required to connect it with the channel guide or other work support, avoiding the necessity for long sections of flexible pipe, which are carried in

and about the working parts of the machine to communicate with the nozzle.

While in the present embodiment of my invention, I have shown the moistening device as employed on a common type of sewing machine, it is obviously applicable to any other type of fastening machine, my invention not being limited in that respect, nor to the particular part of the stitching mechanism selected or used as a nozzle for supplying water to the channel.

My invention contemplates the use of a moistening device with any work guide or support which can be adapted for such use and the employment thereof in connection with any desired type of leather working machine.

It will be obvious that my invention is not limited to the specific details or to the arrangement of parts herein shown for illustrative purposes only, but that the same may be modified and varied within wide limits without departing from the spirit thereof.

What I claim and desire to secure by Letters Patent is:—

1. A machine of the type described comprising stitching mechanism, operating means therefor, a moistening device, a valve therefor provided with means for opening it, and machine operated means for automatically closing said valve independently of the operation of the stitching mechanism, substantially as shown and described.

2. A machine of the type described comprising stitching mechanism for operating on shoe soles, a sole moistening device, a valve connected therewith, starting and stopping mechanism for said machine, means independent of the starting and stopping mechanism to open said valve upon starting the machine and hold it continuously open during the operation of the machine, and means for closing said valve at desired times regardless of the operation of the stitching mechanism, substantially as shown and described.

3. A machine of the type described comprising stitching mechanism for operating on shoe soles, a sole moistening device, a valve connected therewith, starting and stopping mechanism for said machine, means independent of the latter to open said valve upon starting the machine, and machine operated means for closing said valve, substantially as shown and described.

4. A sole sewing machine having starting and stopping means, a treadle for controlling the same, an operating shaft, a cam thereon, a moistening device having a valve, a bell crank connected therewith, a link or rod slidably connected with said bell crank, and means to move said bell crank and open said valve, substantially as shown and described.

5. A machine of the type described having an operating shaft, a cam thereon, a moistening device having a valve, a bell crank con-

nected therewith, a link or rod slidably connected with said bell crank and means to move said bell crank and open said valve and to permit said link to move into position to be engaged by said cam to close said valve, substantially as shown and described.

6. A machine for operating on shoe soles provided with a shaft and means for applying fastenings in shoe channels, a liquid supplying device having a part arranged to discharge liquid in the channel of a shoe sole operated upon, a valve controlling said supply, means for operating said valve, and shaft controlled means for closing said valve.

7. A machine of the type described comprising in combination a sole channel guide, a moistening device having a supply pipe communicating with a passage in said guide, a valve for said pipe, means for applying power to or disengaging it from said machine, means for opening said valve and holding it open during the operating of the machine, said means being operable in applying power to said machine, and power means for closing said valve, substantially as shown and described.

8. A machine of the type described, comprising in combination a sole channel guide, a moistening device having a valve supply pipe communicating with a passage in said guide, means for applying power to or disengaging it from said machine, means independent of said power applying means for opening said valve and permitting it to remain open during the operation of the machine, and power operated means also independent of said power applying means for closing said valve at desired times, substantially as shown and described.

9. A machine of the type described, comprising in combination a sole channel guide, a moistening device having a supply pipe communicating with a passage in said guide, a valve, means for opening said valve and separate power operated means for closing said valve, substantially as shown and described.

10. In a machine of the type described, an operating shaft, a moistening device having a valve, means connected therewith adapted by its movement to open and close said valve, and a cam on the operating shaft arranged to engage said means to close said valve, substantially as shown and described.

11. In a machine of the type described, stitching devices operating in the channels of shoe soles, a moistening device having an outlet adjacent to said devices and in the channel of a shoe sole operated upon, a valve controlling the supply of moistening liquid thereto, a clutch to disengage the power from said machine, and power means operating independently of the release of said clutch to close said valve, substantially as shown and described.

12. In a machine of the type described,

- stitching devices operating in the channels of shoe soles, a moistening device having an outlet adjacent to said devices and in the channel of a shoe sole operated upon, a valve 5 controlling the supply of moistening liquid thereto, a clutch to disengage the power from said machine having means to operate it, means independent of said clutch operating means and connected with said valve for 10 opening the same simultaneously with movement of said clutch operating means to start the machine and power means operating subsequently to the release of said clutch to close said valve.
- 15 13. In a machine for applying fastenings to leather, a moistening device having a valve to control the supply of liquid and a supply pipe leading therefrom and arranged to discharge said liquid upon the work operated upon, means arranged to open said valve upon starting the machine, and permit it to remain continuously open during the operation of the machine, and power operated means for closing the valve.
- 20 14. A work moistening device for sole fastening machine comprising in combination means moved by the operative for rendering it effective and power operated means for rendering it ineffective.
- 25 15. A work moistening device for sole fastening machines comprising in combination means controlled and moved by the operative for rendering it effective and similarly controlled but power operated means 30 for rendering it ineffective.
- 30 16. A work moistening device for sole fastening machines comprising in combination treadle controlled starting means and power operated stopping means operable at 40 a predetermined point only in the cycle of movement of the machine.
17. A machine of the type described comprising fastening mechanism, power operating means therefor, a clutch to apply the power to and disengage it from said machine, a moistening device, a valve therefor provided with means for opening it, and means operating automatically for closing said valve subsequent to the release of said clutch 45 for stopping the machine, substantially as shown and described.
- 50 18. A machine of the type described comprising stitching mechanism for operating on shoe soles, a sole moistening device, a valve, starting and stopping mechanism to operate said machine, means to open said valve upon starting the machine, and means for closing it subsequent to the action of said stopping mechanism in stopping the machine substantially as shown and de- 60 scribed.
19. A machine of the type described comprising in combination a sole channel guide, a moistening device having a supply pipe communicating with a passage in said guide, a valve, means for applying power to and disengaging it from said machine, means for opening said valve operable in applying power to said machine, and means for closing said valve operating subsequently to 70 disengaging power from said machine.
20. A machine of the type described comprising in combination fastening mechanism for applying fastenings in channels of shoe soles means for operating said mechanism, a moistening device having an outlet adjacent to said mechanism and in the channel of the shoe sole operated upon, a valve controlling the supply of moistening liquid thereto, a clutch to disengage power from said machine, and means operating subsequently to the release of said clutch to close said valve. 75
21. In a machine of the type described fastening mechanism, a moistening device therefor having a valve to control the supply of liquid, a clutch for disengaging power from said machine, and separate means to control the clutch and valve respectively to permit of partial release of said clutch to cause the fastening mechanism to operate 80 slowly without effecting closure movement of the valve of said moistening device, substantially as shown and described.
22. In a machine of the type described the combination of a moistening device having a valve adapted to be opened and closed respectively upon starting and stopping the machine, with means to permit operating the machine at a slower rate of speed through the instrumentality of said stopping mechanism, said means at such time being ineffectual to cause a closure movement of said valve substantially as shown and described. 85
- In testimony whereof, I have signed my name to this specification, in the presence of two subscribing witnesses.
